BRUSH

Robert J. Dunn, Chicago, Ill.

Application November 29, 1933, Serial No. 700,192

3 Claims. (Cl. 15—196)

This invention relates to brushes.

It is an object of this invention to provide an improved brush which is relatively simple and inexpensive in construction and efficient in use.

- 5 Other objects of the invention are: to provide an improved mounting for the metallic bristles of a brush or other like surface-treating or cleaning and polishing apparatus and especially to provide an improved mounting for burnishing 10 brushes; and to provide an improved method for making the brush mounting and for anchoring metallic bristles or tufts of bristles therein so that the bristles will not work loose or be dislodged from the mounting when the brush is in use.
- 15 Another object of the present invention is to provide a brush including a hub and mounting structure which will not shrink when wet or crack or otherwise become ruptured when in use, which has been an objected feature of the prior 20 art brush mounts.

Other objects will appear hereinafter.

The drawing illustrates several typical and preferred embodiments of the invention, and therein:

- 25 Fig. 1 is an elevational view of a typical brush embodying a preferred form of invention, made according to the method thereof;
- Fig. 2 is a transverse sectional view on line 2—2 in Fig. 1;
- 30 Fig. 3 is a sectional view similar to Fig. 2, but showing the bristle mounting of the brush prior to the pouring thereinto of the anchoring filler body;

Fig. 4 is a sectional view on line 4—4 in Fig. 2;

- 35 Fig. 5 is a sectional view illustrating a modified form of brush made according to the method of the invention;

- Fig. 6 is a sectional view illustrating another modified form of brush made according to the 40 method of the invention; and

Fig. 7 is a sectional view illustrating a modification of the invention.

- In the typical and preferred embodiment of the invention shown in Figs. 1, 2 and 3 a brush structure is generally indicated at 10. In its preferred form the brush 10 has the form of a burnishing brush and has tufts of soft metal bristles 11, but the structure and method hereinafter to be described are equally applicable to other forms of 50 brushes, surface treating apparatuses, cleaning and polishing apparatuses, and the like which have metallic bristles, and the term "brush" as used hereinafter is generic to the several types of apparatus mentioned and is so to be construed 55 hereinafter and in the claims.

The brush 10 includes a metallic bristle mounting and hub structure, generally indicated at 12, and comprising an annulus or ring 13. Formed integrally with the ring 13 at the center thereof is a hub or core 14 having a centrally disposed bore 60 or opening 15 formed therein so that the hub may be mounted upon a spindle arbor or the like, for rotation thereby.

Formed integrally with the hub 14 and ring 13 and extending therebetween about midway between the axial ends of the ring 13 is an annular web or wall 16 in which is formed an annular row of radially arranged anchor holes or openings 17 (Fig. 3).

Extending transversely or laterally through the 70 ring 16 and spaced radially therearound are annular rows of openings or anchor holes 18.

In the manufacture of the brush 10 the tufts of soft, metallic bristles 11 are bent or looped midway between their ends and the looped end portions or bases 19 of the bristles are then projected through the holes 18 in the ring 13 into the interior of the ring 13 (Figs. 2, 3 and 4). A flexible tying or binding element in the form of a small flexible wire 20 is then extended around each row 75 of holes 18, inside of the ring 16, through the looped end portions 19 of the tufts of bristles 11; each of these anchoring elements or wires 20 being tied at its ends, as at 21.

A molten filler 22, preferably of soft metal or metallic alloy, is then poured into the ring 16 substantially to fill the latter; the filler flowing into the holes 17 to close the latter, thereby securely anchoring the filler body 22 to the ring 13 and wall 16; while at the same time the filler 80 22 flows into and around the looped end portions 19 of the bristle tufts, as shown in Fig. 2, and thereby securely anchors the metallic bristles 11 to the brush mounting 12 and against displacement therefrom by centrifugal or other forces 85

acting on the bristle tufts to dislodge the same from the brushing mounting 13 when the brush is in use and rotating at high speeds. After the 90 filler pouring operation, the filler body 22 and the bore 15 may be drilled out and there will then be left in the filler body 22 at opposite ends of the bore 15 openings 23 which are coaxial and continuous with the bore 15 for the reception of a spindle or the like, upon which the brush may be mounted for rotation thereby.

100 Substantially the same method as that hereinbefore described is practiced in making the modifications of Figs. 5 and 6 which differ from the brush shown in Figs. 1 to 4 inclusive principally only as to form or design.

In the modification shown in Fig. 5 the brush mounting is generally indicated at 24 and includes a substantially cup-shaped member 25 which has annular side walls 26 and an end wall 27 at one end thereof. In this form of the invention the looped end portions 28 of the tufts of metallic bristles 29 are projected through annular rows of angularly extending openings 30, formed in the member 24, into the cup-shaped interior of the member 24 wherein they are tied by flexible tying or anchoring elements in the form of wires 31, each of which is extended through all the looped end portions 28 of the bristle tufts in a row of the same. A filler body 32, similar to the filler body 22, is then poured into the cup-shaped member 24 and flows into and around the looped end portions 28 of the tufts of bristles 29, thereby securely anchoring the tufts of bristles to the mounting 24. Finally a centrally disposed bore 32 is drilled through the filler body 32 coaxially and continuous with the preformed opening 34 in the wall 27 of the member 25 to receive a spindle or the like upon which the brush may be mounted.

Substantially the same method as that hereinbefore described is also followed in making the modified form of the invention shown in Fig. 6 and which is generally indicated at 35. This form of the invention likewise comprises a bristle or brush mounting 36 which includes a cup-shaped member 37. This cup-shaped member 37 includes side walls 38 and an end wall 39 and extending through these walls 38 and 39 are angularly extending openings 40. The looped end portions 41 of the tufts of soft metallic bristles 42 are projected through the openings 40 into the interior of the cup-shaped member 37 wherein they are tied by flexible anchoring elements in the form of wires 43, after the manner hereinbefore described in connection with the forms of the invention shown in Figs. 1 to 4 inclusive and Fig. 5.

A filler body 44 of soft metal or like equivalent material is then poured into the cup-shaped member 37 so that it flows into, around and between the looped end portions 41 of the bristle tufts 42, thereby securely anchoring the tufts of bristles 42 to their mounting 36. A centrally disposed and tapered opening 45 is then drilled through the soft core or filler body 44 for the reception of a spindle, arbor shaft or the like upon which the brush may be mounted for rotation.

The modification of the invention shown in Fig. 7 comprises a hand brush generally indicated at 46 and including soft metallic bristles 47 which have their looped end portions 48 projected into recesses 49 which are formed in and extend transversely through the brush mounting 50; the recesses 49 being arranged in annular rows. Each of these recesses 49 has a constricted neck portion 51 and extending around each row of recesses 49 and projected into the constricted neck portions 51 thereof is a flexible tying or anchoring element in the form of a wire 52. These wires 52 are projected through the looped end portions 48 of the bristle tufts 47 and their ends are tied together on the opposite side of the brush mounting 50 from the bristles 47.

The metallic filler body, such as 22, in the brush mounting effectively cooperates with the body or tying elements or wires, such as 20, to anchor the inner end portions or bases, such as 19, of the bristles in the mounting and against dislodgement therefrom and, in the case of the

brush shown in Figs. 1 to 4 inclusive the web 16 and anchor holes 17 therein cooperate with the filler body 22 to anchor the latter in the mounting. And it will be found that when a brush and mounting constructed according to the present invention are in use the same will not shrink, as do the prior art wooden brushes when wet, nor will it crack or otherwise become ruptured as do the prior art brushes and their mountings.

It may be found desirable, for the sake of lightness, to make the entire brush mounting, such as 12, except the filler 22, of wood or other equivalent material that is lighter than metal and in this case the molten filler 22 would be poured into the hollow interior or core of the mounting as, for example, into the ring 13, to complete the mounting, and when therein would function as hereinbefore set forth. The invention contemplates this modification and the same is considered within the scope of the appended claims.

While I have illustrated and described the preferred form of construction for carrying my invention into effect, this is capable of variation and modification, without departing from the spirit of the invention. I, therefore, do not wish to be limited to the precise details of construction set forth, but desire to avail myself of such variations and modifications as come within the scope of the appended claims.

Having thus described my invention what I claim as new and desire to protect by Letters Patent is:

1. A brush comprising a substantially annular mounting having rows of radially arranged holes or openings formed therein, and said holes extending between the radially outer and radially inner surfaces of said mounting; said mounting having an integral transverse web extending thereacross between its axial ends and said web having axially extending anchor holes or openings formed therein; rows of bristles having butts extended through said radially extending holes into the interior of said mounting; a flexible tying member extended through the butts of the bristles in each of said rows of holes; and a relatively soft filler body in said mounting and substantially filling the same and cooperating with said tying members to anchor said bristles to said mounting; said filler body being interspersed through said anchor holes to anchor said filler body in said mounting and to said web.

2. A brush comprising a substantially annular mounting having rows of radially arranged holes or openings formed therein, and said holes extending between the radially outer and radially inner surfaces of said mounting; said mounting having an integral transverse web extending thereacross between its axial ends and said web having axially extending anchor holes or openings formed therein; rows of bristles having butts extended through said radially extending holes into the interior of said mounting; a flexible tying member extended through the butts of the bristles in each of said rows of holes; and a relatively soft filler body in said mounting and substantially filling the same and cooperating with said tying members to anchor said bristles to said mounting; said filler body being interspersed through said anchor holes to anchor said filler body in said mounting and to said web; said web having an enlarged centrally arranged portion projecting from the axial sides thereof and providing a core for said mounting; said core having an axially extending opening formed therein for the reception of a supporting member for the brush.

3. A brush comprising a substantially annular mounting having rows of radially arranged holes or openings formed therein, and said holes extending between the radially outer and radially inner surfaces of said mounting; said mounting having an integral transverse web extending thereacross between its axial ends and said web having axially extending anchor holes or openings formed therein; rows of bristles having butts extended through said radially extending holes into the interior of said mounting; a flexible tying member extended through the butts of the bristles in each of said rows of holes; and a relatively soft filler body in said mounting and substantially filling the same and cooperating with said tying members to anchor said bristles to said mounting; said filler body being interspersed through said anchor holes to anchor said filler body in said mounting and to said web; said web having an enlarged centrally arranged portion projecting from the axial sides thereof and providing a core for said mounting; said core having an axially extending opening formed therein for the reception of a supporting member for the brush; and said filler body having axially extending openings formed therein coaxial with and on opposite ends of the said opening in said core and for the reception of said supporting member.
